METALLIC COVER FOR BOXES, TINS,
FLASKS, AND LIKE ARTICLES

Egisto Biffi, Milan, Italy

Application November 28, 1930, Serial No. 498,854
In Italy August 11, 1930

1 Claim. (Cl. 220—54)

This invention relates to the special construction of a container, wherein the cover or lid is secured to the body of the container by collars rolled into both members and there is provided on the flange of the cover a rip strip which is limited by a weakening groove. The novelty of the invention resides in the fact that a connection with such a designed container, the notched or grooved weakening channel is provided in the upper part of the flange on its inner surface. The object thereof is to effect a direct removal of the rip strip in the upper part or summit of the cover flange whereby a flanged cover with a bearing edge remains which when the container is open effects by its own weight a tight closure of the container. The direct removal of the rip strip is ensured because the curved edge remaining on the cover offers a great resistance to the forces resulting from the bearing off and these forces become effective only in the upper part of summit of the cover flange by the flange of the container's body engaging in the cover flange.

Containers of the first named type are known wherein the weakening channel is provided on the upper edge of the cover collar or flange but this arrangement does not prevent a displacement of the weakening channel. A cover is also not obtainable which can be subsequently placed on the collar of the container's body and thereby produce a good closure.

It is also known to provide the notch or groove in the upper part of summit of the cover collar but without the simultaneous arrangement of a counter-collar engaging in the aforesaid collar. This construction of the container has also the above-mentioned drawbacks which are obviated by the present invention.

The invention is shown by way of example in the drawings, in which:—

40 Figure 1 is a side elevation partly in section of one form of the invention.

Figure 2 shows a similar view of the same constructional form with the rip strip being removed, and

45 Figure 3 is an enlarged detail view.

Similar characters of reference designate corresponding parts throughout the several views.

Referring now more particularly to the drawings there is provided a tin container 1 which 50 may have any desired shape and is closed by a cover 2. A tight connection or joint between cover and container is produced by providing the body of the container and the depending flange 3 of the cover 2 with interengaging annular members in the form of rolled collars 8, 8' fitting one

within the other and preferably made at the same time in one operation. In order to ensure the tight closure, the top edge 10 of the container 1 is flanged inwardly and engages in an annular groove 11 in the cover 2 wherein if necessary a 60 packing material 9, such as rubber, may be provided (Figure 3).

The strip 3' to be removed from the flange 3 is limited by an annular weakening groove 4 located medially of the upper and lower edges of 65 and on the inner surface of the collar 8'. In order to facilitate the removal of the strip, it is interrupted by a transverse slot 5 and provided at one end with a tongue 6 wherein a hole 7 is provided for the insertion of an instrument 7' in 70 the form of a ring, metal thread, cord or the like. When the tongue 6 is pulled, the strip 3' is detached or removed to leave the upper half of the collar 8' which cooperates with the rolled collar 8 on the body to form a secondary seat- 75 ing and substantial sealing portion.

In view of the foregoing description it is believed that a further detailed description is entirely unnecessary. Likewise it is believed that the advantages of the invention will be readily 80 apparent.

What I claim is:—

In a metallic closure of the character described, the combination with a container provided near its upper edge with an outwardly rolled annular collar, of a cover having a depending flange provided near its lower edge with a complementary rolled collar for snug engagement about the rolled collar on the body in such manner as to lock the cover on the container, the inner surface of 85 the rolled collar on the flange of the cover being provided with a weakening groove extending entirely throughout the inner periphery and medially of the upper and lower edges thereof to provide a lower rip strip portion, said rip strip 90 portion having a slot extending from the free outer edge which interrupts the same, and a tongue extending from the rip strip portion adjacent one edge of the slot to facilitate the removal of the strip and permit removal of the 100 cover.

EGISTO BIFFI.
